U.S. Appl. No. 29/570,023, filed Jul. 1, 2016, Kennedy et al.
(Continued)*Primary Examiner* — Mitchell Siegel*(74) Attorney, Agent, or Firm* — Wolf, Greenfield &
Sacks, P.C.(57) **CLAIM**The ornamental design for a lacrosse head, as shown and
described.**DESCRIPTION**

FIG. 1 is a bottom, front, right side perspective view of a
lacrosse head showing our new design;
FIG. 2 is a front elevation view thereof;
FIG. 3 is a right side elevation view thereof;
FIG. 4 is a rear elevation view thereof;
FIG. 5 is a top plan view thereof;
FIG. 6 is a bottom plan view thereof;
FIG. 7 is a fragmentary, top, right side perspective view of
a portion thereof; and,
FIG. 8 is a fragmentary, top, right side perspective view of
a portion thereof.
The dash-dash broken lines represent portions of the
lacrosse head that form no part of the claimed design. The
dot-dash broken lines represent boundaries of the claimed
design and form no part of the claimed design.

1 Claim, 5 Drawing Sheets(56)
